Primary Examiner — Selina Sikder*(74) Attorney, Agent, or Firm* — McCoy Russell LLP(57) **CLAIM**

The ornamental design for a system controller enclosure, as shown and described.

DESCRIPTION

FIG. 1 is a perspective view of a system controller enclosure depicting a first embodiment of a new design;
 FIG. 2 is a front elevational view thereof;
 FIG. 3 is a rear elevational view thereof;
 FIG. 4 is a left side elevational view thereof;
 FIG. 5 is a right side elevational view thereof
 FIG. 6 is a top plan view thereof; and
 FIG. 7 is a bottom plan view thereof.

FIG. 8 is a perspective view of a system controller enclosure depicting a second embodiment of a new design;
 FIG. 9 is a front elevational view thereof;
 FIG. 10 is a rear elevational view thereof;
 FIG. 11 is a left side elevational view thereof;
 FIG. 12 is a right side elevational view thereof;
 FIG. 13 is a top plan view thereof; and,
 FIG. 14 is a bottom plan view thereof.

The broken line portion of the figure drawings is included to show unclaimed subject matter only and forms no part of the claimed designs.

1 Claim, 8 Drawing Sheets(56)
